(57) **CLAIM**

I claim the ornamental design for the diesel injector sleeve, as shown and described.

DESCRIPTION

FIG. 1 is a bottom side perspective view of a diesel injector sleeve showing my new design;

FIG. 2 is a top side perspective view of FIG. 1;

FIG. 3 is a side elevation view of FIG. 1;

FIG. 4 is a bottom plan view of FIG. 1;

FIG. 5 is a top plan view of FIG. 1; and,

FIG. 6 is another side view of FIG. 1.

1 Claim, 6 Drawing Sheets

FIG. 1

FIG. 2

FIG. 3

FIG. 4

FIG. 5

FIG. 6
